CONTACT ASSEMBLY

Gilbert H. Fagley, Pittsfield, Mass., assignor to
General Electric Company, a corporation of
New York

Application April 10, 1934, Serial No. 719,900

3 Claims. (Cl. 200—166)

My invention relates to electrical contacts and more particularly to an improved stationary contact assembly for contact making voltmeters.

A contact making voltmeter is a voltage responsive circuit controller which is usually used as the master control element of voltage regulating systems of the type employing a tap changing transformer or an induction voltage regulator. It usually comprises a main operating solenoid which is mechanically connected to a pivotally mounted contact beam in such a manner that the beam is rocked or moved on its pivot in accordance with changes in the voltage of a circuit energizing the operating solenoid. The contact beam usually carries two contacts which cooperate respectively with two stationary contacts. In operation, when the voltage falls below a predetermined value, one of the contacts on the contact beam engages one of the stationary contacts, thereby completing a circuit for causing the regulator to raise the voltage, whereas if the voltage is above a predetermined value the other contact of the contact beam engages the other stationary contact, thereby completing a circuit for causing the regulator to operate in such a manner as to reduce the voltage. There is usually a small range of motion of the solenoid and contact beam in which none of the contacts are in engagement and this range corresponds to the voltage band of the regulating system.

One of the main problems encountered in the design and operation of contact making voltmeters is the problem of securing proper and long lived contact action. It has been found that if the stationary contacts are rigidly mounted there is a tendency for a contact rebound and contact chattering to take place upon the closing of the contact. This causes contact arcing which is harmful to the contact surface and which also shortens the useful life of the contacts. By resiliently mounting the stationary contacts this rebound and chattering can be reduced, but with an ordinary resilient mounting there is sufficient counterforce produced by the resilience of the mounting still to cause some rebound and to throw the movable contacts out of engagement with the stationary contacts before the voltage has returned to a value within the regulating band with the result that the contacts will again engage. This results in unnecessary operation of the regulator apparatus. If the stationary contacts are mounted on extremely resilient supporting means the last mentioned effect can be greatly reduced, but I have found that with such a mounting the stationary contacts tend to vibrate,

due either to the vibration of the meter itself, when it is energized from an alternating current circuit, or from the fact that the motion imparted to the stationary contacts by engagement with the movable contacts of the contact beam sets the former in motion and due to the extreme resilience of the support this motion is continued in a vibratory manner for an appreciable time and with an appreciable amplitude of vibration after the contacts separate.

In accordance with my invention I have provided a simple and novel stationary contact assembly for contact making voltmeters in which the stationary contacts are movable with the contacts of the contact beam in such a manner as to offer a minimum resistance to this motion and in which means are provided for preventing undesirable vibratory motion of the stationary contacts. As a result of the offering of a minimum of resistance to the motion of the contacts of the contact beam, these contacts can always assume a position which corresponds to the voltage of the energization of the operating solenoid and consequently a regulating operation can be completed in a fewer number of steps than heretofore because of the negligible tendency of the stationary contacts to throw the movable contacts away before the regulating change has been completed. Similarly, the minimum resistance to motion of the movable contacts minimizes contact rebound and hence contact arcing. I achieve the above results through the use of an extremely light and resilient supporting means for the stationary contacts combined with a stop member for preventing vibration of the stationary contacts, and also through the use of specially constructed stationary contacts of extremely light weight.

An object of my invention is to provide a new and improved contact mounting.

Another object of my invention is to provide a new and improved electrical contact construction.

A further object of my invention is to provide a new and improved stationary contact assembly for contact making voltmeters.

My invention will be better understood from the following description taken in connection with the accompanying drawing and its scope will be pointed out in the appended claims.

In the drawing, in which like reference characters designate similar elements throughout the several views, Fig. 1 is a perspective view of the upper portion of a contact making voltmeter embodying the features of my invention; Fig. 2 is a longitudinal sectional view of a preferred form of my improved stationary contact assembly;

Fig. 3 is an end view of the contact assembly; Fig. 4 is a bottom view of the assembly and Fig. 5 is a detailed perspective view of one of the stationary contacts.

5 Referring now to the drawing and more particularly to Fig. 1, the contact making voltmeter shown therein consists essentially of a base 1, on which is mounted an enclosed operating solenoid 2 having a core 3 which is connected by 10 means of a resilient operating connection, or spring, 4, to a pivotally mounted contact beam 5 having movable contacts 6 and 7 carried thereon. Cooperating respectively with movable contacts 6 and 7 are a set of resiliently mounted 15 stationary contacts 8 and 9.

The normal operation of the meter is such that if the energization of the operating solenoid 2 falls below a predetermined value corresponding to a predetermined low voltage the core 3 moves 20 downwardly thereby causing movable contact 7 to engage stationary contact 9, whereas if the energization of the solenoid 2 is above a predetermined value corresponding to a voltage above a predetermined high value, the core 3 moves 25 upwardly thereby causing the movable contact 6 to engage the stationary contact 8.

The contact assemblies for the stationary contacts 8 and 9 are identical and consequently only the details of the contact assembly for stationary contact 8 are shown in the remaining figures. Referring now to Figs. 2, 3, and 4, it will be seen that the assembly for stationary contact 8 comprises an insulating support 10 to which is fastened by means of a bolt 11 a strip of metal 12. 30 Fastened to this strip of metal by any suitable means, such as by riveting, is an extremely flexible and resilient blade spring 13 to the outer end of which is fastened the contact 8. For preventing vibration of the contact 8 as a result of 35 the extreme resilience of the spring 13 I provide a stop 14 underneath the spring 13 so that when the contact 8 is in normal position the stop 14 bears against the spring 13 and prevents vibration of the contact 8.

40 One convenient way of combining the strip 12 and stop 14 is to bend the sides of the strip 12 downwardly so as to form side members 15 and to provide one of these side members with an integral projection which when bent inwardly 45 forms stop member 14. The other projection may be made less wide than 14 so that when bent inwardly it forms a guard member 16 for stop 14. The member 16 is a guard for stop 14 in the sense that it prevents powdered contact 50 metal from getting between spring 13 and its stop 14, as otherwise this powdered metal would cause sticking. In order to increase the resilience and flexibility of the spring 13, this spring is 55 shown as having a cut-away center section, as can be seen clearly in Fig. 4.

60 Strip 12 is also provided with a dished-in portion 17 which acts as a stop to limit the motion of contact 8 and hence to limit the motion of the contact beam. This limiting of the contact beam motion renders more uniform the action of the usual holding coils, which are shown enclosed at 18 and 19 respectively.

I have found that if the blade spring 13 and the stop 14 are made of different metals, some 70 reaction takes place between these two metals which appears to be a sort of electrolytic reaction or form of thermocouple effect, and after a short time the spring tends to adhere slightly to the stop so that the stationary contact is not 75 lifted away by the torque obtained from the

solenoid under normal voltage changes. Such a reaction may be prevented in numerous ways, such as providing the stops with glass beads or other similar material, but I have found that if the spring and stop are made of the same 5 metal, this action does not take place, and the metal which I at present prefer to employ is stainless steel for both blade spring 13 and the stop 14.

In order further to improve the operation of 10 the meter and increase its accuracy, I construct the stationary contacts in a special manner. As shown more clearly in Fig. 5, this contact is of hollowed out construction. This decreases its weight, whereby it is more easily moved by the 15 force produced by the operating solenoid, thus further reducing the tendency of contact rebound to occur. In the form which I at present contemplate employing, the stationary contact 8 is a cup-shaped piece of metal having a rounded 20 bottom or contact surface roughly conforming to the shape of a sphere and having cut away side faces. This cutting away of the side faces produces two distinct advantages. The first is, that it provides openings between the inside of the 25 contact and the atmosphere so that air may pass therethrough thereby providing ventilation and cooling of the contacts, which is important, since there is more tendency for the contact to become heated for a given current by reason of the reduced conducting cross section resulting from its 30 hollow form. The second advantage of the cut-away side faces is that it provides at least two separate surfaces in the same plane for attachment to the blade spring 13. I have found that 35 if the surface for attachment to the blade spring is circular, it is very difficult to obtain a satisfactory and strong weld between the contact and the blade spring, and as welding is the means which I at present prefer to employ for fastening 40 the stationary contact to the blade spring, it is obviously important that a satisfactory weld be produced. However, by providing two surfaces, or a discontinuous circular surface, a strong weld is produced between each separate surface and 45 the spring 13.

While I have shown and described a particular embodiment of my invention, it will be obvious to those skilled in the art that changes and modifications may be made without departing 50 from my invention, and I, therefore, aim in the appended claims to cover all such changes and modifications as fall within the true spirit and scope of my invention.

What I claim as new and desire to secure by 55 Letters Patent of the United States is:

1. A stationary contact assembly for use in contact making voltmeters comprising, in combination, a normally horizontally supported strip of metal having integral downwardly bent sides, 60 inwardly bent projections on said sides, a relatively thin blade spring fastened to said strip so as to pass between said strip and said projections and normally adapted to rest against one of said projections as a stop, the other projection 65 forming a guard member for said stop, and a contact carried by said spring, said projection which forms a guard member extending between said contact and the other projection which forms the stop.

2. A stationary contact assembly for use in contact making voltmeters comprising, in combination, a normally horizontally supported strip of stainless steel having integral downwardly bent sides, an inwardly bent projection on one of said 75

sides, a thin blade spring of stainless steel of the same composition as said strip fastened to said strip so as to extend between said projection and said strip and normally resting in a substantially 5 unstressed condition on said projection as a stop, and a hollow contact with ventilating openings therein fastened to the under side of said spring.

3. In a contact making voltmeter having an operating solenoid and a pivoted contact beam 10 connected to be rocked by said solenoid, the combination of a stationary contact for cooperation with said contact beam, said stationary contact

being of hollow construction so as to reduce its weight thereby improving the accuracy of the meter, said contact also having ventilating openings therein, a thin blade spring supporting said stationary contact, said spring being so resilient as to offer a negligible resistance to the motion of said stationary contact, and a stop placed under said spring for partially supporting it in a substantially unstressed condition and preventing vibration of said contact as a result of the extreme 10 resilience of said spring.

GILBERT H. FAGLEY.
